[57] CLAIM

The ornamental design for a trash bag roll retainer/dispenser, as shown and described.

DESCRIPTION

FIG. 1 is a top rear perspective view of the closed end of the trash bag roll retainer/dispenser of the invention positioned within a garbage container; the garbage container shown in phantom and not forming a part of the invention;

FIG. 2 is a top, front perspective view of the open end of the trash bag roll retainer/dispenser, the interengaging clips shown in phantom and not forming a part of the invention; FIG. 3 is an end elevational view of the same trash bag roll retainer/dispenser taken at the open end;

FIG. 4 is a side elevational view of one side of the same trash bag roll retainer/dispenser; the other side of the dispenser having the same appearance;

FIG. 5 is an end elevational view of the same trash bag roll retainer/dispenser taken at the closed end;

FIG. 6 is a top plan view of the same trash bag roll retainer/dispenser; the interengaging clips of the parts of the dispenser shown in phantom and not forming a part of the invention; and,

FIG. 7 is a bottom plan view of the same trash bag roll retainer/dispenser; the interengaging clips of the part of the dispenser shown in phantom and not forming a part of the invention.
